CLAIM

The ornamental design for a printer media feed plate with a flip-up guide wall, as shown and described.

DESCRIPTION

FIG. 1 is a perspective view of a printer media feed plate with a flip-up guide wall in accordance with the present invention shown with the guide wall in lowered position for feeding conventional media widths, such as letter, legal, or A-4 sized media;

FIG. 2 is a perspective view of the printer media feed plate of FIG. 1 with the guide wall in an upright position for feeding narrower media;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.
